Specification for Design.

Patented Apr. 27, 1915.

Application filed February 17, 1913. Serial No. 749,045. Term of patent 14 years.

To all whom it may concern:

Be it known that I, WALTER R. GREEN, a citizen of the United States, and residing in the city of Chicago, county of Cook, and State of Illinois, have invented a new, original, and ornamental Design for Drop Side Mud-Guards, of which the following is the specification, reference being had to the accompanying drawings, forming a part thereof.

In the drawings: Figure 1, is a side elevation of drop side mud guard showing my design. Fig. 2 is a fragmentary perspective view taken on the line II—II, Fig. 1.

I claim:

The ornamental design for a drop side mud guard as shown.
